UNITED STATES PATENT OFFICE

RAUL FEDERICO ZIMMERMANN, OF BUENOS AIRES, ARGENTINA

THERMIC INTERRUPTER FOR ELECTRICAL CURRENT

Application filed June 27, 1929, Serial No. 374,187, and in Argentina February 5, 1929.

The present invention relates to a novel thermic interrupter of electrical currents actuated by the expansion or contraction of solid members produced by temperature

5 changes of a solid, liquid or gaseous body to which such interrupter is connected, and wherein the temperature at which the current is cut off may be varied by changing the position of a pointer on a graduated scale.

10 The invention also contemplates other objects which will appear hereinafter and which are set forth clearly in the appended claims.

In order that the present invention may 15 be clearly understood and readily carried into practice, same has been represented, by way of example, on the accompanying illustrative drawings, in which:—

Fig. 1 illustrates a longitudinal section of 20 the device according to the invention.

Fig. 2 shows a view of the apparatus in the plane C—D (Fig. 1), with the member 5 in section, the drawing showing only those members engaged with the bearing points 25 of lever 15.

Fig. 3 is a view in the plane A—B (Fig. 1), showing merely the parts connected directly to the circuit closing members.

Fig. 4 is a sectional view in the plane E—F 30 of Fig. 1.

Fig. 5 is a detail view of the variable temperature adjusting and graduating device and, finally,

Fig. 6 is a front elevation of the apparatus.

Throughout these figures, like or corresponding parts are designated by similar characters of reference.

The thermic interrupter according to the present invention comprises three independent parts, viz: the member 1, the interrupter proper, and the condenser 27.

The member 1 is that part entering in contact with the solid, liquid, or gaseous body the temperature variations of which actuate the interrupter. Within the said member 1

45 is placed the member 2 of the interrupter and secured with one of its ends to the base 5 by means of screw 6, and with the other end to the rod 3 at the point 4.

The member 2 has a coefficient of expansion 50 different than that of the rod 3 so that when

their temperatures change (heat being transmitted from 1 to 2 and from 2 to 3), the free end of rod 3 is displaced relative to the end of 2 secured to 5.

The interrupter is covered by a cap 8 secured to part 5 by means of two screws 32 capable of being sealed. The knob 9 may be rotated externally of the cap 8 and its shaft 10 moves the forked member 11 secured by means of a screw 12 to the adjusting screw 55 13 screwed into the rod 3. Thus it will be seen that by changing the eccentricity of the pin 10 from the center of 9 in connection with the member 11 the screw 13 will be turned a greater or lesser degree without a corresponding increase or decrease of turning action of the knob 9.

A member provided with two points 14 imparts the longitudinal movement of 13 (when rotating or when such movement is imparted 70 by 3) to the lever 15 fulcrumed at 16 and formed of the two points 17 secured to the member 2. A spring 18 bearing with its ends between the head of a screw 19 and lever 15 provides for the latter being held normally 75 in contact with the points 17. At the end of lever 15, electrically insulated by means of plates 20, there is secured a member 21 which secures in position the bridge 22 engaging the two contacts 23 and closing the 80 circuit between both members. The two contacts 23 are fed with current over two plates 24 traversing the cap 8 and which are provided externally thereof with terminals 25 to which are secured the wires carrying the current to be cut off, to which terminals may be connected also, by means of members 26, the condenser 27 the function of which is to avoid the formation of an arc on the contacts in certain cases. The terminals 25 are covered 85 by cap 28 secured in position by means of screw 29.

Members 2 and 3 may be integral instead of being independent members, and they may be made of any adequate material.

Assuming the expansion coefficient of 2 be greater than that of 3, an increase in the temperature will produce a displacement of the free end of 3 from left to right (Fig. 1) such movement being transmitted to 13 and 14 and

from the latter to lever 15 which, bearing upon the points 17, will be moved angularly, the center of such movement being at 16 and, thus, the member 22 will be moved away from

- 5 23 thereby cutting off the feed of electrical current. Should the temperature fall, then 3, 13, and 14, will move in opposite direction and the lever 15, due to the action of spring 18, will press upon 22 and against contacts 10 23 establishing again the circuit.

Rotating manually the knob 9 this produces a rotation of screw 13 which is thus moved to or from the member 3, and the moment at which the current is cut off corresponds with 15 a certain position to the right or to the left of the free end of three (3) and, thus, with different temperatures corresponding with the graduations as indicated by the pointer 30 of knob 9 on the scale 31 provided at 8. 20 By loosening the adjusting screw 12, the position of 13 relative to 11 may be varied, thus providing for the interrupting temperature corresponding exactly with the graduations of scale 31.

25 Evidently, different modifications of construction and detail may be made without departing from the scope of the present invention as clearly set forth in the appended claims.

30 Having thus fully described and ascertained the nature of my said invention and the manner in which the same is to be performed, what I claim as of my exclusive invention and proprietorship is:

35 1. The combination with a circuit controlling device; a thermo responsive means having an opening near one end; fixed fulcrums on opposite sides thereof; a lever operatively connecting the circuit controlling device and 40 the thermo responsive means and having intermediate and outer fulcrum engaging portions in a common plane, the intermediate portion entering the opening and the outer portions engaging the fixed fulcrums; and 45 adjustable means constituting a fulcrum and engaging the intermediate portion.

50 2. The combination with a circuit controlling device; a thermo responsive means having an opening near one end; fixed fulcrums adjacent said opening; a lever operatively connecting the circuit controlling device and the thermo responsive means and having intermediate and outer fulcrum engaging portions in a common plane, the intermediate 55 portion entering the opening and the outer portions engaging the fixed fulcrums; adjustable means carried by the thermo responsive means and engaging the intermediate portion; and means for regulating the adjusting 60 means.

65 3. The combination with a circuit controlling device; a thermo responsive means having an opening near one end; fixed fulcrums adjacent said opening; a lever operatively connecting the circuit controlling device and

the thermo responsive means and having intermediate and outer fulcrum engaging portions, the intermediate portion entering the opening and the outer portions engaging the fixed fulcrums; adjustable means carried by the thermo responsive means and engaging the intermediate portion; a forked member engaging the adjustable fulcrum means; and means coactive with the fork of the member for moving the same. 75

4. The combination with a circuit controlling device; a thermo responsive means having an opening near one end; fixed fulcrums adjacent said opening; a lever operatively connecting the circuit controlling device and the thermo responsive means and having intermediate and outer fulcrum engaging portions, the intermediate portion entering the opening and the outer portions engaging the fixed fulcrums; adjustable means carried by the thermo responsive means and engaging the intermediate portion; a forked member engaged on the adjustable fulcrum means; and a manually operable rotary member eccentrically engaging the fork of the latter member to control the same. 85

5. The combination with a circuit controlling device; a thermo responsive means having an opening near one end; fixed fulcrums adjacent said opening; a lever operatively connecting the circuit controlling device and the thermo responsive means and having intermediate and outer fulcrum engaging portions, the intermediate portion entering the opening and the outer portions engaging the fixed fulcrums; adjustable means carried by the thermo responsive means and engaging the intermediate portion; a forked member connected to the adjustable fulcrum means; a manually operable rotary member eccentrically engaging the fork of the said member to control the same; and means yieldably supporting the lever at a point beyond the fulcrums. 100

6. The combination with a circuit controlling device; a thermo responsive means; fixed fulcrums adjacent said means; a lever operatively connecting the circuit controlling device and the thermo responsive means and having one end straddling one end of the latter with a portion engaging loosely said thermo responsive means, said end of the lever being also engaged with the fixed fulcrums; adjustable means carried by the thermo responsive means to fulcrum the loosely engaged end therewith; and regulating means for the adjustable means. 115 120 125

In testimony whereof I affix my signature.

RAUL FEDERICO ZIMMERMANN.
